(57) **CLAIM**

The ornamental design for a “building wall face”, as shown and described.

DESCRIPTION

FIG. 1 is a perspective view of the wall face;
FIG. 2 is a frontal view thereof;
FIG. 3 is a top view thereof, the bottom and side views being substantially similar.
FIG. 4 is a frontal view of a second embodiment of the wall face;
FIG. 5 is a frontal view of a third embodiment of the wall face;
FIG. 6 is a frontal view of a fourth embodiment of the wall face;
FIG. 7 is a frontal view of a fifth embodiment of the wall face; and,
FIG. 8 is a frontal view of a sixth embodiment of the wall face.
Features shown in broken lines in the drawings are not part of the claim.
